KITE RELEASE FOR PARACHUTES AND GLIDERS

Robert F. Doerr, Portsmouth, Ohio

Application July 24, 1939, Serial No. 286,288

5 Claims. (Cl. 244—155)

This invention relates to an attachment for a kite, the general object of the invention being to provide a holder for holding a parachute and a glider, with a traveling member on the kite string which will release the parachute and glider when the traveling member reaches a point on the string adjacent the kite.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a perspective view of the invention showing the same on a kite string.

Figure 2 is a perspective view of the trigger parts.

Figure 3 is a view of the main tube through which the kite string passes.

Figure 4 is a view of the small tube carried by the traveling member.

Figure 5 is a view of the clip used for holding the string of the kite in the tube of the traveling member.

Figure 6 is a view of the parachute in open position.

In these drawings the holder is shown at A and includes an elongated bar 1 having a housing forming sheet 2 fastened to its lower part, the sheet being looped over the bar with its major portion depending from the bar to form a housing for the parachute F, the housing tapering forwardly and the parachute being folded and having its major portion inserted into the housing as shown in Figure 1. The parachute is formed of tissue paper or the like and has the strings 3 attached thereto with the strings connected together by a weight 4, the weight 4 having a loop 5 attached thereto. An angle clip 6 is fastened to the upper end of the bar 1 and has a forwardly extending part formed with a slot 7 and adjacent the front end of the bar an angle strip 8 is attached to its upper edge, the free and short arm 8' of the strip having a hole therein for receiving a rod 9 which passes through the bar 1 and through a post 10 depending from an intermediate part of the bar 1 and having a substantially horizontally arranged bar 11 attached to its lower end. The rod 9 passes through a small tube 12 which connects the post 10 to the horizontal bar

11, with the lower end of the rod 9 connected by a flexible member 14 with one end of a plate 15 which has its other end held in a notch 16 in a trigger member 17, said trigger member having its upper end pivoted in a notch in the rear end of the horizontal bar 11 as shown at 18. A weight 19 is connected to the rear edge of the trigger member 17 and the lower end of said member is beveled and carries a headed pin 20 and a plain pin 21 which extends in front of the headed pin. A long tube 22 has sliding movement through a sloping hole 23 in the forward end of the horizontal bar 11 and said tube has an elongated longitudinally extending slot 24 therein and an enlarged opening 25 adjacent its lower end with said lower end of channel shape in cross section as shown at 26. A flexible member 27 connects the front end of the tube 22 with the front portion of the bar 1 for limiting downward movement of the tube and said front end of the bar 1 is formed with a substantially bayonet slot 28 and a guide 29. The traveling member is shown at B and consists of a card 30 having a slot 31 therein extending from a point adjacent the center of the card through the lower edge thereof with the slot terminating in a round hole located above the center, said hole receiving the slotted tube 32, see Figure 4, which has a plate 33 attached to an intermediate part thereof which, in turn, is attached to the card for firmly supporting the tube 32 in an inclined position on the card with the card engaging an intermediate part of the tube. A locking clip 34 which includes the tubular part 35 and the diverging wings 35' is rotatably arranged on the tube 32, this clip when in one position enabling the kite string S to be passed through the slot 31 through the slot 32' of the tube 32 into the tube and then by rotating the clip the slot 32' will be closed to prevent escapement of the kite string.

A glider G is adapted to be placed on the bar 1 with its tail structure passing through the clip 6 with the horizontal part of the tail structure passing through the slot 7 and the front end of the glider is provided with a loop 40 through which the rod 9 passes for holding the glider on the bar 1.

The kite string is passed through the tube 22 and through the loop 29 and the slot 28, the loop 29 and slot 28 being so formed as to hold the kite string firmly to the bar 1 so as to connect the device to the kite string and this is preferably done adjacent the kite. The glider is placed on the bar 1 with its rear end held in the clip 6 and the loop 40 has the rod 9 passed therethrough and

the parachute is folded and placed in the housing 2 with the loop 5 placed over the trigger member 17 with the pins 20 and 21 of the trigger member passing through the slot 24 through the enlargement 25, the head of pin 20 holding the member 17 in engagement with the tube 22 as shown in Figure 1 and in this position of the parts the plate 15 bearing against the lower end of the rod 9 will hold said rod 9 in its upper position with its upper end passing through the hole in the arms 8' of the strip 8.

Then when the kite reaches a height where it is desired to release the parachute and the glider the traveling member B is placed on the kite string, said string passing through the tube 32 and held therein by the clip 35. Then the traveling member B will move up the kite string until it strikes the lower end of the tube 22 which causes the tube 22 to move upwardly and when the enlarged opening 25 of tube 22 comes over the headed pin 20 the member 17 will swing outwardly and downwardly, thus releasing the loop 5 of the strings of the parachute so that the weight 4 will cause the string to swing outwardly and downwardly thus pulling the parachute from the housing 2. Also this movement of the member 17 will cause the plate 15 to swing downwardly thus exerting a pull upon the rod 9 which causes the upper end of the rod to pass through the loop 40 and this releases the glider so that the wind will remove the glider from the bar 1 and said glider will sail away and, of course, the dropping of the weight 4 will act to pull the parachute from the housing 2 and the parachute will open up and slowly descend.

Thus it will be seen that I have provided an attractive attachment for a kite which will permit the user of the kite to release a glider and a parachute after the kite has carried said devices into the air.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. An attachment for a kite comprising a holder for receiving a parachute in folded position, a weight on the strings of the parachute for pulling the parachute from the holder, means for attaching the holder to the string of a kite, a latch member pivotally supported from the holder and engaging the weighted part of the strings, a traveling member adapted to be placed on the string of the kite and means actuated by the traveling member for releasing the latch member to free the weight whereby the weight will pull the parachute from the holder.

2. An attachment for a kite comprising a holder for a parachute and a glider, means for attaching the holder to the string of a kite, a trigger bar for a part of the parachute, a sliding rod for a part of the glider for holding the glider on the holder, means carried by the trigger bar for holding the rod in operative position and for moving the rod to inoperative position when the trigger bar is released, a tube through which the kite string passes, means carried by the tube for holding the trigger bar in holding position but

releasing the trigger bar when the tube is moved upwardly on the string and a traveling member adapted to be placed on the string to move upwardly thereon to engage the tube and moving the same to a position to release the trigger bar. 5

3. An attachment for a kite comprising a holder for a parachute and a glider, means for attaching the holder to the string of a kite, a trigger bar for a part of the parachute, a sliding rod for a part of the glider for holding the glider on the holder, means carried by the trigger bar for holding the rod in operative position and for moving the rod to inoperative position when the trigger bar is released, a tube through which the kite string passes, means carried by the tube for holding the trigger bar in holding position but releasing the trigger bar when the tube is moved upwardly on the string and a traveling member adapted to be placed on the string to move upwardly thereon to engage the tube and moving the same to a position to release the trigger bar, said traveling member comprising a card having a slot therein, a sloping tube passing through the card and having a slot therein registering with the slot in the card for permitting the kite string to be passed through the slot in the card into the slot in the tube and a rotary locking member on the tube. 20 25

4. An attachment for a kite comprising an elongated bar, a member attached to the rear part of the bar and forming a housing for a parachute, a post depending from an intermediate part of the bar, a horizontal member carried by the lower end of the post, a trigger bar pivoted to the rear end of the horizontal member, a tube sliding through the front end of the horizontal member and having a longitudinally extending slot therein through which a kite string can be passed into the tube, a headed pin at the lower end of the trigger bar for entering the slot in the tube for holding the trigger bar in holding position, the slot in the tube having an enlarged rear portion for releasing the headed member when the tube is moved upwardly on the string, means for connecting the front end of the first-mentioned bar to the string of the kite, means for releasably supporting a glider on the first-mentioned bar, said glider having a loop in its front end, a rod passing through the first-mentioned bar and adapted to engage the loop, means for holding the rod in holding position by the trigger bar and for pulling the rod to releasing position when the trigger bar is released, the parachute having a weight at the lower end of its strings and a loop connected with the weight for passing around the trigger bar and a traveling member adapted to be placed on the kite string for moving the tube upwardly to release the trigger bar. 40 45 50 55

5. An attachment for a kite comprising a frame, means for attaching the frame to a kite string, means for holding a glider on the frame such means including a rod passing through a part of the glider, a depending member pivotally connected at its upper end with the frame and normally held against swinging movement, 65 means for attaching the rod to said swinging member, a traveling member adapted to be placed on the string of the kite and means for releasing the swinging member by the traveling member which causes the swinging member to move the 70 rod to release the glider.

ROBERT F. DOERR.
